CLAIM

The ornamental design for a portable pipe end preparation tool, as shown.

DESCRIPTION

FIG. 1 is a side elevational view of a portable pipe end preparation tool showing my new design;

FIG. 2 is a top plan view thereof;

FIG. 3 is a front elevational view taken from the left of FIG. 1;

FIG. 4 is a rear elevational view taken from the right of FIG. 1;

FIG. 5 is a bottom plan view thereof;

FIG. 6 is a side elevational view of the side opposite that shown in FIG. 1.

FIG 1

FIG 2

FIG. 3

FIG. 4

FIG. 5
